DENTAL CONTAINER FOR INDIVIDUAL REMOVABLE ITEMS

Alan J. Perfect, Allentown, N.J., assignor to
Johnson & Johnson, New Brunswick, N.J.

Filed Dec. 20, 1974, Ser. No. 534,613

Term of patent 14 years

Int. Cl. D24—02

U.S. Cl. D24—1 R

FIG. 1 is a perspective view of a dental container for individual removable items;

FIG. 2 is a top plan view of the container of FIG. 1;

FIG. 3 is a side view of the container of FIG. 1;

FIG. 4 is a bottom plan view of the container of FIG. 1;

FIG. 5 is an end view of the container of FIG. 1; and

FIG. 6 is a perspective view of the container of FIG. 1 from the same perspective as in FIG. 1 but with the cover raised.

I claim:

The ornamental design for a dental container for individual removable items, as shown.
